PRESSING MACHINE

Ernest Davis, Syracuse, N. Y., assignor to The Prosperity Company Inc., Syracuse, N. Y., a corporation of New York

Application August 1, 1930, Serial No. 472,333

15 Claims. (Cl. 68—9)

This invention relates to pressing machines such as garment or laundry presses.

The principal object of the invention is to devise a safety or control lock for the pressing machine operating mechanism which will not lock the control mechanism for the press in operated position until the pressing elements have come together, thus making it necessary for the operator to hold his hands on the operating manuals until all danger of getting a hand between the pressing elements or jaws is passed.

A further object of the invention is to devise locking means for locking the control mechanism for a pressing machine in operated position, said locking means being operated by the stopping or substantial stopping of air flow through one of the pressing elements.

A further object of the invention is to provide a novel buck construction having a padding thereon which is particularly economical to build and well adapted for use with machines having air flow through the buck.

Another object is to provide a pressing element or jaw with a current of air through the padding of the jaw and valve means which cut off the current of air upon the press jaws coming into contact.

Another object is to devise a pressing or ironing machine with a safety or control lock for the operating mechanism, which is operated by the stopping of a current of air through the face of one of the pressing elements or jaws, which also operates valve means to cut off the flow of air through the press jaw.

Other objects and advantages of the invention will be pointed out and become apparent as the description proceeds.

The invention consists in the novel features and in the combinations and constructions hereinafter set forth and claimed.

In describing this invention, reference is had to the accompanying drawings in which like characters designate corresponding parts in all the views.

Figure 1 is a side elevation of a pressing machine embodying my invention.

Figure 2 is a view, mostly in section, showing press operating means and control means, and the connections between the control means.

My invention is designed primarily for use on pressing machines of the head and buck type having a movable pressing head 10 mounted on the yoke 11 which is pivoted at 12 to a back leg 13 of a pressing machine frame 14. A fixed pressing element or buck 17 is supported on a neck 18

mounted on the pressing machine frame 14. The yoke 11 is moved about its pivotal connection 12 to move the pressing head 10 into and out of contact with the buck 17 to close and open the press.

The yoke 11 is moved by actuating mechanism 5 including a link 20 pivoted at its upper end to the yoke 11 at 21, and pivoted at its lower end at 22 to a bell crank lever 23 which is pivoted at 24 to the pressing machine frame 14. A spring 25 connected at one end to the forwardly extending arm of the bell crank 23 and at its other end to the pressing machine 14 normally holds the press in open position.

A fluid motor 27 is oscillatively mounted at 28 on the pressing machine frame 14. The fluid motor 15 27 includes a piston rod 30 pivotally connected at 31 to the forwardly extending arm of the bell crank 23. Operation of the fluid motor 27 moves the bell crank 23, against the tension of the spring 25, to straighten the toggle link formed by the link 20 and the upstanding arm of the bell crank lever 23, thus moving the yoke 11 to close the press. The mechanism, thus far described, is of the conventional type and forms no part of the present invention.

The fluid motor 27 is controlled by the operator through fluid pressure control mechanism having push buttons 34 and 35. The push button 34 operates the valve in the valve casing 36. The valve casing 36 includes a normally open 30 exhaust valve 37 which is provided with a stem 38 extending through the end of the valve casing 36. This stem 38 is compressible for reasons which will be explained later. A rocker arm 40, pivotally mounted at 41 on a bracket extending from the valve casing 36, operates the exhaust valve 37. A bell crank lever 42, pivotally mounted at 43 on the pressing machine frame, transmits motion of the push button 34 to the rocker arm 40 to operate the rocker arm 40 and through it 40 to the valve 37.

The rocker arm 40 may also be operated by a plunger 45 extending from fluid-operated means in the diaphragm chamber 46. A diaphragm 47, mounted in the diaphragm chamber 46, operates 45 the plunger 45 when pressure or a difference in pressure is applied behind the diaphragm 47. A spring 48 normally holds the plunger 46 and diaphragm 47 in retracted position.

A portion of the diaphragm chamber 46 communicates through a port with a valve chamber 50 having a valve 51 therein which is connected by a stem 52 with the diaphragm 47. When the diaphragm 47 is in retracted position, the valve 51 will be open as shown in Figure 2 of the drawings.

A valve casing 55 contains a normally closed intake valve 56 and a normally open exhaust valve 57 which are joined together by a spacer rod 58 so that they operate as a unit. A spring 59 holds the valves 56 and 57 in their normal positions. The valve 57 is provided with a stem 60 over which is mounted a sleeve 61 having one end closed. A spring 63 is mounted in the sleeve 61 and bears at one end against the closed end of the sleeve and at the other end against the valve stem 60. The members 60, 61, and 63 taken together comprise a compressible valve stem which is similar to the valve stem 38 of the exhaust valve 37. The purpose of having the valve stems compressible will be explained later. The valves 56 and 57 are operated by a rocker arm 65 which is pivoted at 66 to a bracket on the valve casing 55. A bell crank 67 transmits motion of the push button 35 to the rocker arm 65 to operate the rocker arm and through it the valves 56 and 57.

The rocker arm 65 may also be operated by a plunger 70 projecting through the wall of a diaphragm chamber 71. A diaphragm 72 located within the diaphragm chamber 71 operates the plunger 70 when a difference in pressure is applied or occurs behind the diaphragm 72. A spring 73 normally holds the plunger 70 and diaphragm 72 in retracted position. The diaphragm chamber 71 behind the diaphragm 72 communicates with a valve chamber 75 in which is mounted a valve 76 which is connected by a rod 77 with the diaphragm 72. The valve 76 controls the current of fluid through a conduit 116 connected with a conduit 117 extending to the pressing element or jaw 80. When the diaphragm 72 is in normal retracted position, the valve 76 will be open as shown in Figure 2 of the drawings and when the diaphragm is in operated position, the valve 76 will be closed.

The fixed pressing element or buck includes a body portion 80 having an air blowing chamber 81 covered by a perforated plate 82. The perforated plate 82 is covered by shredded material such as steel wool 85. A marginal casing 86 passes under the edges of the shredded material around the sides of the buck and extends upwardly and inwardly a slight distance over the sides of the shredded material to hold the same against lateral displacement. The marginal casing 86 is composed of a material through which air cannot pass. The shredded material such as steel wool 85 and the marginal casing 86 are held on the buck by a cover 88 which passes over the shredded material and marginal casing and under the marginal edges of the body portion 80 of the buck. The covering 88 may be secured to the body portion 80 of the buck by suitable means such as a gathering cord 89 which draws the lower edges of the covering 88 inwardly to hold the cover tightly in place.

A relief valve 95 in a valve casing 96 is normally held closed by a spring 97. A handle 98 pivoted at 99 to the valve casing 96 is provided to open the valve 95 in order to permit the escape of air from the diaphragm chambers 46 and 71.

The fluid motor 27 is of the conventional type having a cylinder 100 which contains a piston 101 connected to the piston rod 30 which operates the press actuating mechanism in the manner previously described.

The diaphragm chambers 46 and 71 are adapted to be connected to a source of fluid flow and, in the embodiment shown herein, the diaphragm chambers and the buck 17 are connected to a

source of high pressure which is the same source as used for the power supply for the motor 27. Other sources of fluid or air flow, of course, may be utilized, but the preferred embodiment herein utilizes the power supply because the control valves to the motor 27 may then be used to serve another function, namely, to control the air flow through the buck 17 as well as control the air flow to the motor. A separate source of air flow also need not be provided.

The operation of the machine is as follows:

Working fluid, such as air, is supplied through a fluid supply line 105 to the valve casing 55. If the intake valve 56 is in its normally closed position, no air can pass through the valve casing 55. Operation of the push button 34 will be ineffective to supply air to the fluid motor 27 unless the push button 35 is also operated to open the intake valve 56.

When the push button 35 is actuated to operate the valves in the valve casing 55, air will flow from the fluid supply line 105, around the open intake valve 56, through the valve casing 55, and through a pipe 106 to the valve casing 36. A branch pipe 107 connects the pipe 106 with the fluid motor 27. If the exhaust valve 37 is open, air will escape from the pipe 106 through the valve casing 36 and open exhaust valve 37, and sufficient pressure will not build up in pipe 106 and branch pipe 107 to operate the fluid motor 27. If the push button 35 is actuated to close the valve 37, pressure will build up in the pipe 106 and branch pipe 107 and the piston 101 will be operated. Air in the valve casings 36 and 55 will flow through the conduits or ducts 110 and 111 respectively into the diaphragm chambers 46 and 71 respectively. As long as the pressing head 10 is not in contact with the buck 17 and air-flow through the buck 17 is not obstructed, air will pass from the diaphragm chambers 46 and 71 through the normally open valves or valve means 51 and 76 respectively and through the pipes 115, 116 respectively, pipe 117, air blowing chamber 81 and up through the buck. While the air is thus free to escape through the pipes 115, 116 from the diaphragm chambers 46 and 71 respectively, a sufficient difference in pressure will not occur or build up in these diaphragm casings to operate the plungers 45 and 70 against the springs 48 and 73.

When the pressing head 10 comes into contact with the buck 17, air-flow through the buck will be cut off and a difference in pressure will build up in the diaphragm casings 46 and 71 and the diaphragms 47 and 72 will be moved to control the position of, or particularly to close, the valves 51 and 76 respectively, and to actuate the plungers 45 and 70 to lock the valves in their respective valve casings 36 and 55 in operated position. It is observed, therefore, that the movable jaw 10 serves also as a valve to cut off the flow of air through the buck 17 and conduit 117, and other means may be provided if desired to serve this function. The press is thus locked in closed position and it is no longer necessary for the operator to hold the push buttons 34 and 35 in operated position. It will be apparent that the method of locking the valves, as above described, possesses advantages not found in the conventional system in which the piston in the motor cylinder uncovers a port in the cylinder wall and admits working fluid under pressure to the diaphragm chambers to lock the valves. On machines having valves which are locked by pressure from a

port opening, the locking may occur too soon if the operating links get out of adjustment or the padding on the pressing elements acquires a permanent set. A further disadvantage of locking valves with pressure from a port opening is presented if the operating links get out of adjustment so that the piston cannot uncover the port when the work between the pressing elements is very thick. With the improved locking means of this invention, it is impossible for the valves to be locked before the pressing elements come together but when the movable pressing element comes in contact with the work the valves will always lock regardless of the thickness of the work.

It will be seen, therefore, that the movable jaw or head 10 provides means creating an operating pressure in the conduits 115 and 116 which actuates the pressure responsive means 47 and 72 to hold the control means or valves 37 and 56, 57 in their operated position. The diaphragms 47 and 72 may be described as having the function of controlling the position of the valves 37 and 56, 57. The actuation of the diaphragms 47 and 72 also actuates, or particularly closes, the valve means 51 and 76.

When the operator wishes to open the press, he may do so by operating the handle 88 which opens the exhaust valve 95 in the valve casing 96. Air is then free to escape from the diaphragm chambers 46 and 71 through the pipes 120 and 121, pipe 122, and valve casing 96. The pipes 120 and 121 and the pipe 122 are of larger cross-sectional area than the conduits or fluid connections 110 and 111 so that air will escape from the diaphragm chambers 46 and 71 faster than it can be supplied through the conduits 110 and 111. As the air pressure in the diaphragm chambers 46 and 71 becomes less the springs 48 and 73 will restore the plungers 45 and 70 respectively to their normal retracted positions and the valves in the valve casings 36 and 55 will be free to return to normal position.

When the exhaust valves 37 and 57 return to open position air in the fluid motor 27 will exhaust through the pipe 107, pipe 106 and valve casings 36 and 55. When the pressure in the fluid motor 27 is thus reduced, the spring 25 will move the press actuating mechanism to open the press as previously described.

It should be noted that when the diaphragms 47 and 72 operate to lock the valves in the valve casings 36 and 55 in operated position the valves 51 and 76 will be moved into closed position to completely cut off all air-flow to the buck. The diaphragms 72 and 47 have therefore a double function, namely, to hold the valves 56, 57 and valve 37, respectively, in operated position, and also to close the valve 76 and valve 51, respectively. The operation of the valves 76 and 51 comprises a separate function for the pressure responsive means represented by the diaphragms, irrespective of the control of and the locking in operated position of the valves for another function, namely, the control of the motor means.

The diaphragms or pressure responsive means 47 and 72 operate as a consequence of a difference of fluid pressure in their respective chamber 46 and 71. When the pressing elements or jaws 10 and 17 are separated, there is a free flow of fluid or air through the pressing jaw and as a consequence the fluid pressure in the conduits 116 and 117 and the diaphragm chambers 46 and 71 is substantially that of the outer air if

the frictional pressure drop through the conduits and buck is not considered. Now when the head 10 contacts with the buck 17, the free flow of fluid or air through the buck is materially reduced which brings about a material change or produces a distinct difference in the fluid pressure in the conduits 116 and 117 and the diaphragm chambers 46 and 71 when the pressing elements 10 and 17 are in contact and when they are separated. The diaphragms 47 and 72 are sensitive to this difference or variation of pressure in their respective diaphragm chambers and are moved thereby to lock the control valves 37 and 56, 57 in operated position.

The diaphragm 47 holds the valves 37 and 51 in closed position. The stems of these valves may be of such length that both valves will seat at exactly the same time. Even if such were the case however, it would be likely that one valve seat would wear more than the other so that when the diaphragm 47 moved into position to bring one of the valves into contact with its seat the other valve would not make contact, or make contact too lightly to completely stop the flow of working fluid. To overcome this difficulty, the valve stem 38 is made resilient as shown in the drawings. As the diaphragm 47 is operated by fluid pressure it will move the valve 37 into contact with its seat before the valve 51 closes. Due to the resilient stem 38 the diaphragm 47 may continue to move, compressing the resilient stem 38, until the valve 51 is seated and the flow of working fluid to the pipe 115 cut off. In similar manner the valve stem of the valve 57 is made resilient in the manner previously described.

While I have illustrated and described the preferred embodiment of my invention, various changes and modifications may be made without departing from the spirit of the invention as set forth in the appended claims.

What I claim is:

1. In a pressing machine, in combination, co-operative pressing elements adapted to open and close on the work; operating mechanism to open and close the press; control means operable to supply working fluid to the operating mechanism to close the press; a conduit for supplying fluid to one of the pressing elements for escape through the face of said pressing element; means connected with the conduit for locking the control means in operated position so that said locking means will be operated by pressure built up in the conduit when the flow of fluid through the face of the pressing element is retarded as the pressing elements come into contact with each other.

2. In a pressing machine in combination co-operative pressing elements adapted to open and close on the work; said pressing elements having faces opposed to each other and coming in contact when the press is closed; operating mechanism to open and close the press; control means operable to supply working fluid to the operating mechanism to close the press; means normally holding the control means in position to prevent the flow of working fluid to the operating mechanism; operator-operated means to move the control means into operated position to supply working fluid to the operating mechanism; means to pass a current of air through the face of one of the pressing elements, including a conduit; means connected with the conduit for locking the control means in operated position so that said locking means will be operated by

- the change in pressure in the conduit when the current of air through the face of the pressing element is substantially prevented as the faces of the pressing elements come in contact.
5. 3. In a pressing machine in combination co-operative pressing elements adapted to open and close on the work; said pressing elements having faces opposed to each other and coming in contact when the press is closed; operating mechanism to open and close the press; means to provide air-flow through the face of one of the pressing elements, including a conduit, common control means operable to supply working fluid to the operating mechanism to close the press and 10 to supply air for air-flow through said face of one of the pressing elements; means connected with the conduit for locking the control means in operated position, said means being operable by the pressure built up in the conduit when 15 the air flow through the face of the pressing element is retarded by the contacting of the faces of the pressing elements.
4. In a pressing machine in combination a buck; a head movable toward and from the buck; actuating mechanism for the head; operating mechanism for the actuating mechanism, including fluid motor means; means to provide air flow through the face of the buck, including an air conduit normally closed valves for controlling 20 the supply of working fluid to the motor means; operator-operated means for moving the valves into operated position to supply working fluid to the motor means and to supply air-flow to the buck; means connected with the air-flow conduit for locking the valves in operated position, said means being operable by pressure built up in the air-flow conduit when the air-flow through 25 the buck is retarded by the face of the press head coming in contact with the face of the buck.
5. In a pressing machine in combination, co-operative pressing elements adapted to open and close on the work; operating mechanism to open and close the press; a conduit for supplying fluid to one of the pressing elements for escape through the perforated face thereof; and means connected with the conduit for locking the operating mechanism so that said locking means will be operated by the pressure built up in the conduit when said flow of fluid through the perforated pressing element is substantially cut off by reason of the closing engagement of said elements.
6. In a pressing machine in combination co-operative pressing elements adapted to open and close on the work, operating mechanism to open and close the press, a conduit for supplying fluid to one of the pressing elements for escape through the face of said pressing element, normally closed valve means connected to a source of fluid supply for admitting fluid to the conduit, a normally open valve in the conduit, and pressure responsive means connected with the conduit and closing the normally open valve means by pressure in the conduit when the flow of fluid through the face of the pressing element is retarded as the other pressing element contacts therewith.
7. In a pressing machine in combination co-operative pressing elements adapted to open and close on the work, operating mechanism to open and close the press, including fluid motor means, a conduit for supply fluid to one of the pressing elements for escape through the face of said press-
- ing element, normally closed valve means connected to a source of fluid supply for admitting fluid to the conduit and to the fluid motor means, a normally open valve in the conduit, and pressure responsive means connected with the conduit and closing the normally open valve means by pressure in the conduit when the flow of fluid through the face of the pressing element is retarded as the other pressing element contacts therewith.
8. In a pressing machine in combination co-operative pressing elements adapted to open and close on the work, operating mechanism to open and close the press, control means operable to supply working fluid to the operating mechanism to close the press, a conduit for supplying fluid to one of the pressing elements for escape through the face of said pressing element, means connected with the conduit for locking the control means in operated position so that said locking means will be operated by pressure built up in the conduit when the flow of fluid through the face of the pressing element is retarded as the other pressing element contacts therewith, and a normally open valve in the conduit operated by the locking means to close the conduit to the passage of fluid when the movable pressing element contacts with the other pressing element.
9. In a pressing machine in combination, co-operative pressing elements adapted to open and close on the work, operating mechanism to open and close the press, control means movable to operated position to effect the flow of working fluid to the operating mechanism to close the press, a conduit connected to one of the pressing elements for fluid flow through the face of the pressing element which flow is restricted when the pressing elements engage and adapted to be connected to a source of fluid flow, a pressure responsive means connected with the conduit and controlled by the difference in pressure in the latter when the pressing elements are in open and closed position, and means operatively connecting the pressure responsive means to the control means to lock the latter in operated position.
10. In a pressing machine in combination, co-operative pressing elements adapted to open and close on the work, operating mechanism to open and close the press, control means movable to operated position to effect the flow of working fluid to the operating mechanism to close the press, a conduit connected to one of the pressing elements for fluid flow through the face of the pressing element which flow is restricted when the pressing elements engage and adapted to be connected to a source of fluid flow, the control means also controlling the flow of fluid in the conduit, a pressure responsive means connected with the conduit and controlled by the difference in pressure in the latter when the pressing elements are in open and closed position, and means operatively connecting the pressure responsive means to the control means to lock the latter in operated position.
11. In a pressing machine in combination, co-operative pressing elements adapted to open and close on the work, operating mechanism to open and close the press, control means movable to operated position to effect the flow of working fluid to the operating mechanism to close the press, a conduit connected to one of the pressing elements for fluid flow through the face of the pressing element which flow is restricted when the pressing elements engage and adapted to

- be connected to a source of fluid flow, a pressure responsive means connected with the conduit and controlled by the difference in pressure in the latter when the pressing elements are in open and closed position, and valve means operatively connected to the pressure responsive means and controlling the flow of fluid in the conduit to prevent the flow of fluid when the pressing elements contact with each other.
12. A fluid pressure control mechanism comprising valve means having an inlet and an outlet, means connected with the valve means to initially operate the same, fluid pressure operated means connected with the valve means to hold the same in operated position, a port in communication with the fluid pressure operated means and adapted to be connected through the inlet of the valve means with a source providing a flow of fluid, a second port in the fluid operated means through which fluid passes and adapted to be connected with means which restricts the flow therethrough to control the fluid pressure operated means, a normally open valve also controlling the second port and connected with the fluid operated means so that the actuation of the latter closes the valve, and means to restore the valve means and the valve controlling the second port to their initial positions.
13. A fluid pressure control mechanism comprising valve means including a valve chamber having an inlet and an outlet, a normally closed intake valve within the chamber controlling the inlet, and means to initially operate the intake valve; fluid pressure operated means connected with the intake valve to hold the same in open position; a port of the fluid pressure operated means through which fluid pressure passes and adapted to be connected with means which restricts the flow therethrough to control the latter; a normally open valve controlling the port and connected with the fluid pressure operated means so that actuation of the latter closes the valve; a fluid connection between the fluid pressure operated means and the valve chamber; and means to restore the normally closed intake valve

and the normally open valve to their initial positions.

14. A fluid pressure control mechanism comprising valve means including a normally open exhaust valve which opens upon release of pressure of the pressure operated means and the initial closing means, a valve chamber having an inlet and outlet, and means to initially close the exhaust valve; fluid pressure operated means connected with the exhaust valve to hold the same closed; a port in the fluid pressure operated means through which fluid pressure passes and adapted to be connected with means which restricts the flow therethrough to control the latter; a normally open valve controlling the port and connected with the fluid pressure operated means so that actuation of the latter closes the valve; a fluid connection from the fluid pressure operated means to the inlet, and means to restore the normally open valve controlling the port to initial position.

15. A fluid pressure control mechanism comprising valve means including a normally open exhaust valve, an intake valve normally closing an inlet port and operatively connected with the exhaust valve, a valve chamber between the exhaust and intake valves, an outlet port from the chamber, and means to operate the valves to initially open the intake valve and close the exhaust valve; fluid pressure operated means connected with the valve means to hold the same in operated position; a port in the fluid pressure operated means through which fluid pressure passes and adapted to be connected with means which restricts the flow therethrough to control the fluid pressure operated means; a normally open valve controlling the port and connected with the fluid pressure operated means so that actuation of the latter closes the valve; a fluid connection between the fluid pressure operated means and the valve chamber; and means to restore the normally open exhaust valve, the normally closed intake valve and the valve controlling the port in the fluid pressure means to their initial positions.
